RADIATOR TEMPERATURE CONTROL SYSTEM

Elmore J. Sanders, San Gabriel, Calif.

Application March 23, 1951, Serial No. 217,252

11 Claims. (Cl. 123—41.05)

1

This invention relates to improved fluid circulating apparatus particularly adapted for circulating air in a temperature control system, as for instance in controlling the operating temperatures of an internal combustion engine.

In my copending application, Serial Number 217,253, filed March 23, 1951, on "Fluid Circulation Systems," I have disclosed a novel type of air circulating temperature control system adapted not only to create the usual draft of cooling air through an engine radiator or the like when required, but also to create a warm air circulation through or about the radiator or other equipment during non-cooling periods. More specifically, the apparatus shown in that application includes a specially constructed rotor or fan having an adjustable shutter portion rotatable with the fan by which the fan is convertible between an axial flow cooling condition and a non-cooling condition, in which the rotor acts as a centrifugal impeller discharging warm air radially outwardly. Baffle or shroud means disposed about the fan direct the radially discharged warm air axially toward the radiator and/or the main engine compartment to circulate and warm both.

A second application, Number 217,251, March 23, 1951, on "Fluid Circulating Apparatus," discloses a fluid circulating system similar to the above, but in which the circulation is effected, not by a specially constructed rotor, but by a conventional axial flow fan used in combination with a proximately positioned stationary or non-rotating shutter, the fan being convertible to a centrifugal impeller by closing of the shutter. In the device shown in this second application, the fan and shutter are positioned between the engine and radiator, and baffle means disposed about the fan divide the radially discharged warm air into two axial streams, one stream being deflected forwardly toward the radiator and the other rearwardly to circulate and warm the engine compartment.

The present application is directed to the provision of a second form of stationary shutter circulation system in which the fan and adjacent shutter, instead of being located between the engine and radiator, are preferably positioned forwardly of both the engine and radiator. This arrangement, like the other stationary shutter system, has the advantage of maximum ruggedness and reliability under extremely adverse conditions, rendering it highly desirable for use in military vehicles and the like. In addition, when the shutter is positioned forwardly of the radiator, it may in its closed condition very completely

and positively shut off all flow of air to the radiator. Further, by positioning the fan and shutter at a side of the radiator opposite that at which the engine is located, the fan when acting as a centrifugal impeller is enabled to warm both the radiator and engine compartment with a single circulation of air, the air flowing rearwardly from the fan through both the radiator and engine compartment, and then reversing its direction to flow forwardly through the compartment and radiator and back to the fan.

The air directing baffle of the present systems may take the form of a tubular shroud disposed about the fan and converging between the outer portions of the radiator and shutter. Preferably, the shutter assembly extends across and completely closes off the forward end of this tubular shroud.

The above and other features and objects of the present invention will be better understood from the following detailed description of the typical embodiments illustrated in the accompanying drawing, in which:

Fig. 1 is a side view of an engine temperature control system embodying the invention, showing the path of air flow with the shutters in open condition;

Fig. 2 is a view corresponding to Fig. 1 but showing the air flow pattern when the shutters are closed;

Fig. 3 is an enlarged fragmentary front view taken on line 3—3 of Fig. 2 and showing especially the shutter construction; and

Fig. 4 is a view corresponding to Fig. 3 but showing a variational type of shutter.

With reference first to Figs. 1 and 2, I have shown at 10 a conventional water cooled internal combustion engine, in front of which is mounted the usual upstanding radiator 11. Cooling water flows between the upper portions of the engine water jacket and radiator through a hose 12, and between the lower portions of the radiator and jacket through line 13. The engine is contained within a compartment or housing enclosed at its top and sides by the usual hood 14, at its rear by a vertical wall 15, and across a portion of its underside by bottom wall 16.

Cooling air is forced through radiator 11 by a normally axially discharging fan 17 positioned in front of and opposite the radiator. This fan is carried and driven by a shaft 18, projecting forwardly from engine 10 and extending through a central opening 19 in the radiator. Shaft 18 is in turn driven by the engine crank shaft 20 through a belt 21.

2

3

At its forward side, radiator 11 carries a tubular shroud 22, which converges forwardly from its engagement at 23 with the outer portions of the radiator to a forward circular edge 24 of a diameter slightly larger than the fan. Within its forward end, the shroud carries a shutter assembly 25, comprising a pair of relatively rotatable circular sheet metal disks or sections 26 and 27, by which the air flow is controlled. The forward one 26 of these shutter sections is stationarily mounted to the shroud, as by welding about the outer edge of the shutter section at 28. At its rear side, forward shutter section 26 carries a central hub 29 about which the rear shutter section 27 is rotatably mounted.

The two shutter sections are apertured in a manner permitting opening and closing of the shutter assembly by rotation of the rear section relative to the forward section. As seen in Fig. 3, each shutter section may contain a series of 20 circularly spaced radially extending and enlarging apertures 30, between which are formed a series of circularly spaced shutter surfaces 31. As will be appreciated, in the open condition of the shutter assembly, apertures 30 of the rear shutter section are in registry with the apertures of the forward section to permit the passage of air, whereas in the closed condition, the apertures of the two sections are moved out of registry. The rear shutter section is rotatable between these two conditions, in response to changes in engine water temperature, by a thermostat 32 connected into water line 13. The thermostat actuates the shutter by any suitable type of operative connection diagrammatically represented at 33.

Fan 17 of course operates continuously during operation of the engine, the circulation of air by the fan being controlled by opening and closing of the shutter assembly. Whenever the engine water temperature rises to a predetermined value, as for instance 160° F., thermostat 32 opens the shutter assembly to permit fan 17 to create a rearward flow of air through the radiator, past the engine, and out at the underside of the engine compartment. This draft of air through the radiator cools the engine water, whose temperature ultimately falls to a second predetermined value, at which thermostat 32 closes the shutter assembly to prevent further cooling.

When the shutter assembly is closed, fan 17 commences to operate as a centrifugal impeller drawing warm air forwardly from about the engine and through the radiator and discharging it radially outwardly. The radially discharged warm air is directed rearwardly by shroud 22 to flow along the outer portions of the engine compartment to the rear end of the compartment, and then return forwardly along the central portion of the compartment to the central suction portion of the fan. Air warmed by the engine is thus continuously circulated through the radiator and throughout the entire underhood compartment, to prevent cooling or freezing of the radiator or any of the engine parts by cold external air. It is particularly noted that the centrifugally discharged warm air pressurizes the outer portions of the underhood compartment during the rearward flow of the air in a manner preventing the entrance of cold outside air into the compartment. Among other things, the warm air circulation prevents undesired cooling of the lower crankcase portion 34 of the engine, which cooling has in the past caused the

5

development of sludge formations in the lubricating oil. In addition, the engine air is prewarmed before being drawn into the carburetor, and the air having access to the crankcase through the crankcase breather is maintained in warm condition.

In order that fan 17 may operate as an efficient centrifugal impeller, it is important that the shutter assembly be positioned in close proximity to the leading edges 35 of the fan blades 36. Preferably, this positioning should be as close as is practically possible. As seen in the drawing, this positioning in the illustrated preferred form of the invention is such that the axial distance between the shutter assembly and the fan blades is less than the axial extent of the blades.

Fig. 4 represents a variational type of shutter, in which the air passing apertures and intermediate shutter surfaces take a different form than in Fig. 3. Specifically, the apertures in Fig. 4 extend angularly rather than directly radially outwardly, and have a slight curvature.

I claim:

25 1. Temperature control apparatus comprising a liquid containing radiator, a rotating fan facing said radiator and having blades normally discharging air through the radiator, shutter means adjacent said fan operable between open and closed conditions while the fan is in operation, said fan being rotatable relative to said shutter means while the shutter means is in and remains in one of said conditions, said shutter means in closed condition being disposed across a face of the fan in close proximity to the blades thereof to convert the fan directly adjacent the blades thereof to a centrifugal impeller discharging fluid radially outwardly, baffle means positioned in the path of said radially outward flow of fluid and deflecting a portion thereof toward the radiator, and thermostatic control means operable to actuate said shutter means between said condition in accordance with changes in the temperature of the radiator liquid.

45 2. Temperature control apparatus comprising a radiator, a rotating fan facing said radiator and having blades normally discharging air through the radiator, shutter means adjacent said fan operable between open and closed conditions while the fan is in operation, said fan being rotatable relative to said shutter means while the shutter means is in and remains in one of said conditions, said shutter means in closed condition being disposed across a face of the fan directly adjacent the blades thereof to convert the fan to a centrifugal impeller discharging fluid radially outwardly, and baffle means positioned in the path of said radially outward flow of fluid and deflecting a portion thereof toward the radiator.

55 3. Temperature control apparatus comprising a radiator, a rotating fan facing said radiator and having blades normally discharging air through the radiator, shutter means at the suction side of said fan operable between open and closed conditions while the fan is in operation, said shutter means in closed condition being disposed across said suction side of the fan directly adjacent the blades thereof to convert the fan to a centrifugal impeller discharging fluid radially outwardly, baffle means positioned in the path of said radially outward flow of fluid and deflecting a portion thereof toward the radiator, said shutter means including a pair of relatively 65 adjustable sections, and means mounting one of

said sections substantially stationarily with respect to said baffle means.

4. Temperature control apparatus comprising a liquid containing radiator, a rotating fan facing said radiator and having blades normally discharging air through the radiator, shutter means at the suction side of said fan operable between open and closed conditions while the fan is in operation, said shutter means in closed condition being disposed across said suction side of the fan directly adjacent the blades thereof to convert the fan to a centrifugal impeller discharging fluid radially outwardly, baffle means positioned in the path of said radially outward flow of fluid and deflecting a portion thereof toward the radiator, said shutter means including a pair of relatively adjustable sections, means mounting one of said sections substantially stationarily with respect to said baffle means, and thermostatic control means operable to actuate said shutter means between said conditions in accordance with changes in the temperature of the radiator liquid.

5. Temperature control apparatus comprising a radiator, a rotating fan facing said radiator and having blades normally discharging air through the radiator, shutter means adjacent said fan operable between open and closed conditions while the fan is in operation, said fan being rotatable relative to said shutter means while the shutter means is in and remains in one of said conditions, said shutter means in closed condition being disposed across a face of the fan directly adjacent the blades thereof to convert the fan to a centrifugal impeller discharging fluid radially outwardly, and a tubular shroud extending between outer portions of the radiator and said shutter means for deflecting said radially outward flow of air toward the radiator.

6. Temperature control apparatus comprising a radiator, a rotating fan facing said radiator and having blades normally discharging air through the radiator, shutter means at the suction side of said fan operable between open and closed conditions while the fan is in operation, said shutter means in closed condition being disposed across said suction side of the fan in close proximity to the blades thereof to convert the fan to a centrifugal impeller discharging fluid radially outwardly, a tubular shroud converging between outer portions of the radiator and said shutter means for deflecting said radially outward flow of air toward the radiator, said shutter means in closed condition forming a substantially complete closure across said shroud, said shutter means including a pair of relatively adjustable sections, and means mounting one of said sections substantially stationarily with respect to said baffle means.

7. Temperature control apparatus comprising a radiator, a rotating fan facing said radiator and having blades normally discharging air through the radiator, shutter means adjacent said fan operable between open and closed conditions while the fan is in operation, said shutter means being essentially circular and of a diameter approximately equal to the fan, said fan being rotatable relative to said shutter means while the shutter means is in and remains in one of said conditions, said shutter means in closed condition being disposed across a face of the fan in close proximity to the blades thereof to convert the fan to a centrifugal impeller discharging fluid radially outwardly, and baffle means posi-

tioned in the path of said radially outward flow of fluid and deflecting a portion thereof toward the radiator.

8. Apparatus comprising an internal combustion engine, a radiator for cooling liquid from said engine and positioned at a forward side thereof, a normally axial flow fan positioned forwardly of and axially facing the radiator and having angular blades normally discharging cooling air rearwardly through the radiator and over the engine, shutter means extending across the forward side of said fan and operable between open and closed conditions, said shutter means in closed condition being positioned in close proximity to the fan blades to convert the fan to a centrifugal impeller drawing warm air forwardly from over the engine and through the radiator and discharging it radially outwardly, a tubular shroud extending forwardly between the outer portions of the radiator and shutter means to deflect said radially outward flow of air rearwardly through the radiator and into the space about the engine, housing means about the engine confining said rearward flow of warm air, said shutter means comprising a pair of relatively adjustable sections having registerable apertures, and means mounting one of said sections substantially stationarily with respect to said shroud.

9. Apparatus comprising an internal combustion engine, a radiator for cooling liquid from said engine and positioned at a forward side thereof, a normally axial flow fan positioned forwardly of and axially facing the radiator and having angular blades normally discharging cooling air rearwardly through the radiator and over the engine, shutter means extending across the forward side of said fan and operable between open and closed conditions, said shutter means in closed condition being positioned in close proximity to the fan blades to convert the fan to a centrifugal impeller drawing warm air forwardly from over the engine and through the radiator and discharging it radially outwardly, a tubular shroud extending and converging forwardly between the outer portions of the radiator and shutter means to deflect said radially outward flow of air rearwardly through the radiator and into the space about the engine, housing means about the engine confining said rearward flow of warm air, said shutter means comprising a pair of sheet metal disks having registerable fluid passing apertures and relatively rotatable between open and closed conditions, means mounting one of said disks stationarily to the forward end of said shroud, means rotatably mounting the second disk to said one disk, said disks forming a substantially complete closure across the forward end of said shroud in closed condition, and thermostatic control means for actuating said shutter disks between open and closed conditions in accordance with changes in temperature of the engine and radiator liquid.

10. Temperature control apparatus comprising a radiator, a rotating fan facing said radiator and having blades normally discharging air through the radiator, shutter means adjacent said fan operable between open and closed positions while the fan is in operation, said fan being rotatable relative to said shutter means while the shutter means is in and remains in one of said positions, said shutter means in closed position being disposed across a face of the fan in close proximity to the blades thereof to convert the fan to a centrifugal impeller discharging

fluid radially outwardly, the axial distance between said shutter means when in said closed position and said fan blades being less than the axial extent of said blades, and baffle means positioned in the path of said radially outward flow of fluid and deflecting a portion thereof toward the radiator.

11. Apparatus comprising an internal combustion engine, a radiator for cooling liquid from said engine and positioned at a forward side 10 thereof, a normally axial flow fan positioned forwardly of and axially facing the radiator and having angular blades normally discharging cooling air rearwardly through the radiator and over the engine, shutter means extending across the forward side of said fan and operable between open and closed conditions, said shutter means in closed condition being positioned in close proximity to the fan blades to convert the fan to a centrifugal impeller drawing warm air forwardly 20 from over the engine and through the radiator and discharging it radially outwardly, and a tubular shroud extending forwardly between the

5 outer portions of the radiator and shutter means to deflect said radially outward flow of air rearwardly through the radiator and into the space about the engine, said fan being rotatable relative to said shutter means while the shutter means are in and remain in one of said conditions.
